FUEL INJECTION PUMP

Desire J. Deschamps, Rutherford, N. J., assignor
to Deschamps Fuel Injection Corporation, New
York, N. Y., a corporation of New York

Application September 15, 1945, Serial No. 616,532

17 Claims. (Cl. 103—173)

1

This invention relates to fuel injection pumps and has for its object the provision of an improved high speed pump for injecting liquid fuel into the cylinders of internal combustion engines.

Pumps of this kind frequently comprise a plurality of pump cylinders usually referred to as "bushings" or "cylinder bushings," in which operate plungers actuated by suitable reciprocating mechanism to cause the application of pressure to the liquid fuel and its discharge through tubing to the respective engine cylinders. In one form of pump of this type widely used, the length of the period of injection and therefore the quantity of fuel injected by each stroke of the plunger in its cylinder is varied to suit the power demands of the engine by turning the plunger axially on its cylinder.

Mechanism under the control of the engine governor or throttle lever is provided for simultaneously turning the several plungers of the pump to effect control of the output of the pump as a whole, that is, of all the pump cylinders taken together. Difficulties, however, have been experienced in transmitting the rotary motion to the plunger while it is reciprocating, and one of the commonest arrangements in use heretofore has been to provide a cross arm on the plunger to assist in imparting the turning movement thereto. These cross arms, however, must be made integral with the plunger and consequently the cost of the pump plungers has been high. One of the objects of the present invention is to overcome these difficulties, eliminating such T-shaped plungers and providing a construction which is fully as reliable in operation and less expensive to manufacture.

Another object of the invention is to simplify the mechanism for turning the respective plungers in unison.

Another object of the invention is to provide an improved mechanism for adjusting the output of the individual cylinders while the pump is operating in order to facilitate the calibration of the pump.

A further object of the invention is to provide for the adjustment of the output of the individual cylinders from the outside of the pump housing.

A still further object of the invention is to provide for cutting off the fuel delivery at the end of the injection period in a more nearly instantaneous manner than has heretofore been possible.

The various features of the invention will be understood by considering the accompanying

2

drawings and the following detailed description of one embodiment of the invention which is given by way of example. In these drawings:

Fig. 1 is a central longitudinal sectional view of the improved fuel injection pump taken taken on line 1—1 of Fig. 3;

Fig. 2 is a view in elevation looking from the left-hand of Fig. 1;

Fig. 3 is a similar view looking from the right-hand of Fig. 1;

Fig. 4 is a central longitudinal section of a single pumping unit of the pump, drawn to an enlarged scale;

Fig. 5 is a view of certain parts shown in Fig. 4 looking at the bottom of that figure, some of these parts being shown broken away and some in section;

Fig. 6 is a transverse section taken on line 6—6 of Fig. 4;

Fig. 7 is a sectional view taken on line 7—7 of Fig. 2;

Fig. 8 is a transverse section taken on line 8—8 of Fig. 7;

Fig. 9 is a partial end view of the pump looking from the left of Fig. 1 with parts broken away and shown in fragmentary section on line 9—9 of Fig. 1;

Fig. 10 is a fragmentary section similar to that of Fig. 9 showing a modified construction, the section being taken on line 10—10 of Fig. 11;

Fig. 11 is an outside view looking downward on the parts shown in Fig. 10;

Fig. 12 is a sectional view similar to Fig. 10 but taken on line 12—12 of Fig. 11;

Fig. 13 is a sectional view taken on line 13—13 of Fig. 11;

Figs. 14 to 16 inclusive are views of a single cylinder and plunger with a part of the cylinder broken away and shown in section to show the porting of the plunger, the plunger being shown at three different points of its stroke;

Figs. 17 to 19 inclusive are similar views with the plunger at the same point of its stroke but turned on its axis corresponding to different outputs;

Figs. 20 to 25 inclusive are similar views of a modification and correspond respectively with Figs. 14 to 19 inclusive; and

Figs. 26 to 31 inclusive are also similar views of a further modification corresponding to Figs. 14 to 19 inclusive.

Referring now to the accompanying drawings, the pump comprises a main housing 1 which is a cylindrical shell extending somewhat less than one-half the length of the pump and provided

at its inner end with a flange 2 and at its outer end with a flange 3. A mounting flange or plate 4 is adjacent flange 2 by which the pump is secured on the mounting pad of the internal combustion engine. Housing 1 carries a suitable number of pump cylinders or bushings 5, the pump illustrated having nine cylinders. Each cylinder is provided with a reciprocating plunger 6 which, through a tappet mechanism indicated generally by numeral 7, is operatively associated with the pump actuating element which is shown as a floating wobble plate 8, but which may also consist of a plain wobble plate or a face cam. The respective plungers are operated in a well understood manner on their working or fuel-injecting strokes by means of the actuating element 8 and on their return strokes by means of coil springs 9 appropriately associated with the tappet mechanism 7.

The several cylinders 5 are supported in apertures in internal flanges 10 and 11 at the opposite ends of main housing member 1. To restrain the cylinders against longitudinal movement they are themselves flanged at their outer ends as indicated at 12, these flanges 12 being received within counter bores in the apertures for the cylinders in internal flanges 10.

The tappet members 7 are carried in a tappet housing 13 provided with apertures, for guiding the tappet member 7, which are in longitudinal alignment with the apertures in the internal flanges 10 and 11 of main housing member 1 which support the pump cylinders. Tappet housing 13 is provided with an integral cylindrical extension 14 extending toward the inner or right-hand end of the pump and terminating in a flange 15 by which the tappet housing is supported on main housing member 1. The tappet mechanism and wobble plate 8 are enclosed by a cup-shaped cover member 16 having a flange 17 which fits over flange 15, both this cover and tappet housing 13 being secured to main housing member 1 by a series of screws 18 which are tapped into flange 3.

Main housing 1 and mounting flange 4 are secured together not only by means of a series of screws 19 which are tapped into flange 2, but also by means of a hollow tubular supporting member 20 which extends substantially from end to end of the pump. Member 20 is provided with a shoulder 21 which engages the inner surface of internal flange 10 of housing 1 and projects through a central opening in this flange and also in mounting flange 4 and terminates in a threaded portion 22. On this threaded portion 22 there is a nut 23, the inner end of which is turned up tight against the outer surface of mounting flange 4. Hollow supporting member 20 is received in a central opening in internal flange 11 of housing 1 and also in a similar opening in tappet housing 13 and, being firmly secured to mounting flange 4 and the inner end of housing 1, serves to rigidify the entire pump structure.

Hollow supporting member 20 also serves to support the bearings of the shaft 24 of actuating element 8. This is a tubular shaft extending from end to end of the pump and rotating in ball bearings 25 and 26. Adjacent bearing 25 there is a ball bearing 27 constructed to take the endwise thrust on the shaft resulting from the plunger reaction on wobble plate 8. Bearings 25 and 27 are disposed adjacent each other, and their inner bearing races are held in position by means of a nut 28 threaded on an enlargement on shaft 24.

The inner bearing race of bearing 27 is forced against a shoulder formed on the shaft.

The outer bearing race of bearing 27 fits the bore of hollow supporting member 20 and is held therein by means of a snap ring 28, fitting into a groove in this bore. The outer bearing race of bearing 25 is held in position by a spacing sleeve 29, the right-hand end of which is in contact with a lubricant distributor housing 30. Another snap ring 31 at the right-hand end of housing 30 holds both the housing and spacing sleeve 29 in position within hollow supporting member 20. Inner ball bearing 26 is positioned against an internal rib 32 formed on the interior of supporting member 20 and by a snap ring 33.

Actuating element 8 is of the so-called "floating" or non-rotating type, being mounted on a pair of ball bearings 34 constructed to resist endwise thrust. The outer races of these bearings are held in position within the hollow hub of actuating element 8 by means of a snap ring 35. The inner races are mounted on an extension 36 on hollow shaft 24, the axis of this extension being disposed at a suitable angle to that of shaft 24. These bearing races are held in position on this shaft extension by means of a nut 37.

Tubular shaft 24 constitutes merely a supporting shaft for actuating element 8, and the pump is driven by means of a quill or flexible shaft 38. This shaft is splined at 39 for connection to the pump driving shaft provided on the engine, and its opposite end has a squared enlargement 40 which is received within a similarly formed opening adjacent the outer end of hollow shaft 24.

The gasoline or other fuel to be pumped is admitted to the pump through an inlet opening 41, this liquid being usually supplied by means of a transfer pump which introduces it into inlet 41 at a pressure of about 15 lbs. per square inch.

A second opening (not shown) similar and adjacent to inlet 41 is preferably provided for connection to a vapor removing device. The fuel entering inlet 41 is received within an annular inlet chamber 42 within main housing 1 and outside of hollow supporting member 20. From inlet chamber 42 the fuel is admitted to the working space 43 of each of the nine pump cylinders or bushings 5 through inlet ports 44 which are controlled in a manner to be described.

The fuel is ejected from working space 43 through an outlet opening 45 drilled through mounting flange 4. Each of these outlet openings is closed by a thimble-shaped automatic or spring-actuated valve member 46. As the fuel is ejected from the working space 43 it forces valve member 46 open and escapes through an injection passage 47 which is drilled in mounting flange 4 to communicate with one of the openings 48 through which passes one of the holding screws (not shown) which fasten the pump to the engine mounting pad. It will be understood that these screws are of a hollow construction and that each communicates with a duct within the engine leading to the fuel injection valve of one of the engine cylinders.

As indicated in the introduction, the amount of fuel injected into the engine cylinders by the operation of pump plungers 6, or in other words the volumetric outputs of the pumping spaces 43, is adjusted or regulated by axially turning plungers 6. The turning of these plungers controls the closing and opening of ports 44 in a well understood manner.

Although there is shown in Figs. 1 and 4 only a single port 44 for each cylinder 5, each cylinder

der bushing is in fact provided with two of these ports positioned diametrically opposite each other (see Figs. 14-19). The closing and opening of these two ports is controlled by means of two diametrically opposite lugs 49 on each of the plungers 6. These lugs have the same configuration and, as shown in Fig. 1, their upper edges 50 are flat, i. e., at right angles to the axis of the plunger, while their lower edges 51 each have the form of a helix. As shown in Figs. 1 and 4 plunger 6 is at the end of its inward or back stroke and the upper edges 50 of lugs 49 have uncovered the two ports 44, and fuel is free to flow into the working space 43 through these ports from inlet chamber 42.

As plunger 6 moves to the right on a forward or working stroke the outer edges 50 close ports 44 at the instant they pass the right-hand edges of these ports. The injection of fuel into the engine cylinder will therefore start at this point. Injection continues until the inner helical edges 51 of lugs 49 uncover the left-hand edges of ports 44, which then serve as "spill" ports. At this instant the pressure within working space 43 is released and during the remainder of the stroke of plunger 6 whatever fuel remains in space 43 is forced back through these ports 44 into inlet chamber 42.

Because of the helical shape of the inner edges 51 of lugs 49 the farther the plungers 6 are turned or rotated in one direction the longer will be the injection period. Conversely, turning the plungers in the opposite direction shortens the injection period.

The mechanism for turning plungers 6 while they are reciprocating is illustrated in Figs. 1 and 4 to 8 inclusive. One of the principal parts of this mechanism is a small gear 53 arranged for free rotation on each of the cylinders 6 which, for this purpose, has an end portion 52 of reduced diameter projecting to the left of internal flange 11. The thrust of spring 9 is received by gear 53, the right-hand end of this spring bearing against a collar 54 thereon. Consequently, to enable gear 53 to turn easily, even when spring 9 is under full compression, a ball thrust bearing 55 is placed on the right-hand side of gear 53 between it and the surface of internal flange 11 of housing 1. Each of the gears 53 has a pair of elongated fingers 56, the inner faces 57 of which are fixed in spaced parallel relation, as shown in Fig. 5.

At the left-hand end of each of plungers 6 there is a flanged spring retaining sleeve 58, having a longitudinally projecting key portion 59, the sides of which fit with a sliding fit between the parallel spaced surfaces 51. The inner part of key portion 59 rests within a key slot 60 cut in the surface of plunger 6. Spring-retaining sleeve 58 is held in place on the end of plunger 6 by a two-piece retainer ring 61 of wedge-shaped cross section as shown in Fig. 4 which fits within an annular groove in the outer surface of the plunger.

The sloping outer surfaces of the two-piece ring 61 engage an inner conical surface 62 provided at the left-hand portion of sleeve 58. These parts are held in locked position by the pressure of spring 9, the left-hand end of which engages a flange 63 on sleeve 58. Sleeve 58 being thus fixed at the end of plunger 6, key 59 is held immovably in key slot 60 and reciprocates with the plunger, the key, however, being of sufficient length so that it is engaged by the

surfaces 57 of fingers 56 on key driving gear 53 in all positions of the reciprocating plunger.

By means of this construction a change in the angular position of gear 53 will turn the plunger a similar amount whether the plunger is stationary or reciprocating, thereby regulating or adjusting the helical port-controlling edges 51 and hence the amount of fuel injected into the engine cylinders.

10 Referring now to Figs. 7 and 8, the several key driving gears 53, one for each of the nine pump cylinders 5, are interconnected with one another by means of a large idler gear 64 which is mounted for rotation on the exterior of hollow

15 supporting member 20 (see Figs. 8 and 1). Gear 64 rotates on member 20 between the side of internal flange 11 and a snap ring 65 fitted into an annular groove in the surface of this member.

20 Instead of turning the several gears 53 by means of a turning or driving mechanism connected with gear 64, this gear is employed merely as an idler gear and the output control lever is arranged to actuate one of the gears 53, the motion imparted to this one gear being transmitted to all of the others by the idler gear 64.

25 Thus the control lever, indicated at 66, is fixed on the end of a shaft 67 which is arranged to rotate on an outward extension 68 at one side of main housing 1, as shown in Figs. 2, 3 and 6. On the inner end of shaft 67 there is a gear 69 which engages the teeth of the nearest gear 53. The number of teeth in gear 69 may be so chosen as to provide any desired angular movement of output control member 66 in adjusting the pump from zero to maximum output.

It will be understood that it is important to have the outputs of the respective pumping cylinders varied uniformly in order to maintain

40 equality of load between the various engine cylinders. This requires exact adjustment of the helical control edges 51 of the several pump plungers. Such precise adjustment is ordinarily difficult to obtain in a gear driven mechanism, but in the mechanism as above described it is attained because of the fact that the pressure of the liquid in the working spaces 43 of the pump cylinders, when it is released through uncovering of the spill ports 44 by the helical control edges 51, acts upon these helically inclined edges in such a way as to tend to turn all of the plungers in the same direction. The same sides of the respective gear teeth are therefore always maintained in contact and backlash

55 between them is prevented.

Consequently there is never a reversal of the pressure between any of these gear teeth, either between those of any of the gears 53 and idler gear 64 or between the teeth of gear 69 and those of the gear 53 with which it meshes. In other words, the movement of output control lever 66 transmits force through the gear train to move gears 53 in only one direction of movement of the control lever. In its opposite direction of

60 movement the force transmission is also in the opposite direction, that is, the fluid pressure on the helical edges 51 tends to cause gears 53 to rotate and this rotation is restrained by the output control lever 66 and the teeth of the gear train.

65 The utilization of gear 64 as an idler gear and the application of actuating gear 69 directly to one of the plunger rotating gears 53 has the advantage of placing the actuating mechanism on the outside of the pump and frees the central

part of the pump, greatly simplifying the internal construction of the pump beyond that which it is possible to achieve when the central gear 64 is driven directly by the control lever actuating mechanism.

The tappet mechanism 7 is of thimble-like construction as shown in Fig. 4, the skirt 70 of the thimble being cylindrical so as to slide in the guiding apertures in tappet housing 13 and guide the slippers 71, maintaining them in alignment with their respective plungers 6 as they are actuated in their reciprocating movement by the wobble plate 8. Skirt 70 has a predetermined length in order to operate as an effective guide means and spring 9 is telescoped within skirt 70 for a substantial portion of its length. The inner end of plunger 6 bears directly against the end of tappet 7, the compression of spring 9 operating at all times to urge the tappet and slipper 71 against the surface of the wobble plate 8. Tappet 7 "floats" between the end of the plunger and the wobble plate, there being no connection attaching the tappet to the plunger.

In the pump of the present invention the pump cylinders or bushings 5 are not mounted permanently in housing 1 by means of a "press fit," as is customary, but these parts are assembled with a "sliding fit." This makes it possible to remove individual cylinders for servicing and in addition facilitates manufacture of the pump. It is possible to finish grind and lap or hone the bore of the cylinder bushings as separate and interchangeable units instead of requiring that such finishing operations be done after the bushings have been pressed in place in the housing.

There is an objection to assembling the bushings in the housing with a press fit, as it sets up stress in the walls of the bushings which later on sometimes causes distortion of the bore and sticking of the plunger. Also, when the bushings are inserted with a press fit the metal remains under stress of compression so that temperature changes, stress put on the parts when the pump is in operation, and other factors may cause deformation of the bore of such bushings.

By mounting the pump cylinders 5 with a sliding fit in housing 1, provision is made for another feature of the present invention, namely, the calibration or adjustment of the several cylinders of the pump to produce equal outputs from all cylinders. This is of importance because, although the cylinder bushings and other parts of the pump which may affect the output are machined within small tolerances, the accumulation of these tolerances when taken for the several parts which concur in the motion of the plungers and in the location of the ports may be great enough to cause important discrepancies in the timing of the porting and thus of the outputs of the several pumping units of the pump.

Consequently, it is necessary to provide some means for adjusting the individual pumping units to obtain uniformity of output in the calibration of the pump. As shown in detail in Fig. 9, provision is made for rotating each of the pump cylinders 5 independently of the others, so that the cylinder ports 44 can be angularly adjusted with respect to the helical edges 51 of the port control lugs 49 on the plungers. To accomplish this cylinders 5 are provided opposite the internal flange 11 of housing 1 with a series of worm gear teeth 72 preferably formed by milling cuts equally spaced around the circumference of the cylinder, and an adjusting screw 73 having threads 74 engaging these teeth is provided.

These screws, for each of the cylinders 5, are positioned in apertures drilled in flange 11 which open into a circular recess 15 extending around the pump housing. Adjusting screws 73 each have an enlarged portion 76 having inner and outer shoulders at either side and beyond which is a squared end adapted to receive an adjusting wrench. Enlargement 76 is received within a counter bore at the outer end of the adjusting screw aperture.

The adjusting screw is held fixed to prevent longitudinal movement as it is turned in either direction to effect the turning and adjustment of the pump cylinder 5. For this purpose the inner shoulder of enlargement 76 cooperates with a shoulder formed at the bottom of the countersunk portion of the screw aperture and the outer shoulder of enlargement 76 is positioned against a snap ring 77 which is received within annular groove in the counter bore.

To obtain a close fit between these two shoulders which will allow rotation of screws 73 substantially without endwise movement, shim washers 78 are placed at the innershoulder of enlargement 76. In order to facilitate the assembly of screws 73 in their apertures a supply of these washers in varying thicknesses is provided so that an exact fit of the inner and outer shoulders of enlargement 76 can be obtained.

It will be understood that in calibrating the pump each of the cylinders 5 of the pump's nine pumping units is adjusted by applying a wrench to its adjusting screw 73 until the cylinder produces a predetermined volumetric output. Then adjusting screw 73 is locked in position by means of a locking screw 79, the inner end of which is forced against the surface of enlargement 76 as shown in Fig. 9. Locking screws 79 are protected against unintentional release by means of screws 80 which close the apertures in which screws 79 are threaded.

The outer ends of the apertures in which adjusting screws 73 are located are closed by screw plugs 81. Both these screw plugs 81 and screws 80 are accessible for removal within the annular recess 15 in the pump housing, and this recess may be closed to protect these parts and to improve the appearance of the pump by means of a flexible band 82 encircling the pump and clamped in position by means of a connecting screw 83.

In the modification shown in Figs. 1 to 13 inclusive, the construction of the parts for adjusting the cylinders 5 is identical with that just described except the arrangement for locking the parts in adjusted position after calibration. Instead of providing the locking screw 79 for engaging the enlargement of adjusting screw 73, the cylinder bushings 5 are locked directly by means of a friction shoe 84 (Figs. 12 and 13). One of these shoes 84 is provided between each two bushings 5 in a suitable opening provided in internal flange 11a.

Shoes 84 have arcuate surfaces at their opposite ends so arranged that when the shoe is forced outwardly these surfaces will be wedges into frictional engagement with the cylindrical surfaces of the two bushings 5. Each shoe 84 is provided with an adjusting screw 85 which is accessible within annular recess 15a in the pump housing at a point adjacent alternate screw plugs 81 which cover adjusting screws 73. With this construction, after each two cylinder bushings 5 have been adjusted by turning their respective adjusting screws 73 to bring their output to the desired standard, their common locking screw 85 is turned up, forcing the

shoe 84 at its inner end into engagement with these cylinders.

The leakage of liquid from pumping space 43 back to the inlet chamber 42 is prevented by the engagement of the inner face of flange 12 of cylinder bushing 5 with the shoulder formed at the bottom of the countersunk portion of the cylinder aperture in internal flange 10 of the pump housing. A lapped fit is preferably provided at this point. It will be understood that the pressure between these two surfaces increases with the increase of the pressure in pumping space 43 as the plunger advances. In order to maintain the surfaces in contact with one another at all times a spring washer 86, shown in enlarged view in Fig. 4, is provided. To prevent leakage of fuel from inlet chamber 42 between the surface of cylinder bushing 5 and the aperture of internal flange 11, a composition soft rubber packing ring 87 is provided in suitable grooves 88 (Fig. 4) formed in the surface of each cylinder bushing.

The pump is lubricated by oil under pressure supplied from the pressure lubricating system of the internal combustion engine. The oil may be supplied through the open end 89 of driving shaft 38, thence through ducts 90 and 91 drilled in this shaft to the interior of hollow shaft 24. A packing ring 92 is provided to close the clearance space between these two shafts at their right-hand end and force the oil to flow through a drilled passage 93 at the center of shaft 24 into an annular groove 94 formed in a lubricant distributor member 95. Lubricant distributor 95 has a central opening which makes a running fit with the central part of shaft 24; it is held in place by a shoulder at the left of lubricant distributor housing 30 and by a washer 96 fitted into a recess in this housing at the right-hand end of member 95. Member 95 is "floatingly" held in position, that is, it may sometimes rotate with shaft 24 and sometimes remain stationary or rotate more slowly than the shaft.

Distributor 95 has a radial passage 97 between groove 94 and an outer annular space 98 between distributor 95 and housing 30. Opening through the cylindrical part of housing 30 there are a number of radial openings 99 through which the oil may flow to an annular groove 100 on the interior wall of hollow supporting member 20. A number of radial passages 101 conduct the lubricant from groove 100 to a large annular groove 102 formed in the aperture through internal flange 11 which receives hollow supporting member 20.

From this large annular groove 102 there are spaced openings 103, one leading to each of the apertures in which cylinder bushings 5 are positioned. The lubricant then passes through suitable grooves and an inclined passageway 104 to an annular groove 105 in the surface of plunger 6 from which it lubricates the surface of the plunger and is also conducted through a radial opening 106 to a longitudinal passage 107 in the plunger (Fig. 4) which delivers lubricant at its left-hand end to the tappet mechanism 7.

Some of the lubricant escapes between the end of the plunger and the tappet which abuts against it and flows through passages 108 in the cylindrical skirt 70 to lubricate the surface of this skirt in its guiding aperture in the tappet housing. Lubricant also flows through apertures (not shown) in the tappet mechanism to the interior of slippers 71 and lubricates the surface of the wobble plate 8 and bearings 34 and 35. Lubricant escaping from the end of longitudinal aperture 107

in each of the plungers also serves to lubricate the inter-fitting surfaces of key member 59 and key driving fingers 56. Lubricant escapes from radial passages 103 between the outer surface of cylinder bushings 5 and their apertures, both to lubricate these surfaces and the ball thrust bearings 55 and gears 53 and 64.

The lubricant collects in the portion of the pump to the left of internal flange 11, and returns to the interior of the engine. For this purpose a horizontal passageway 109a (Fig. 3) is drilled through a rib 109b formed on the outside cylindrical surface of main housing 1. Passageway 109a extends from the left-hand face of internal flange 11 to the right-hand face of external flange 2. The right-hand end of this passageway communicates with a series of drilled passages shown in dotted lines in Fig. 3, which convey the lubricant to the lowermost of a series of circular openings in extension 117 (Fig. 1), through which the lubricant flows into the interior of the engine housing. A vent passageway 109 is drilled through lubricant distributor 95.

An alternate means of supplying lubricating oil to the lubricating system just described is provided in case the engine on which the pump is to be used has an oil supply opening in the mounting pad. Mounting flange or plate 4 is provided with an opening shown in dotted lines at 120 (Fig. 1). This opening is fitted with a screw plug (not shown) which is removed in case the oil is to be supplied at this point. Opening 120 passes through flange 4 and communicates with a groove 121 machined in the outer end surface of main pump housing 1. A tube 122 conveys the oil from this groove to a drilled passage 123 in internal flange 11 and this passage communicates with annular groove 102.

Referring again to Figs. 14 to 19 inclusive, these figures show the porting and controlling lug arrangement of the cylinders and plungers for fixed timing of the beginning of the injection period. Figs. 14, 15 and 16 show different positions of one of the plungers 6 during a single working stroke, the controlling lugs 49 being turned to the angular position where the pump has zero effective stroke and consequently no output.

In Fig. 14 the plunger is ready to commence a forward or working stroke. In Fig. 15 the plunger has advanced until the forward edges 50 of control lugs 49 have covered inlet ports 44. At the same instant the helical lower edges of lugs 49 are commencing to uncover the lower edges of ports 44 which serve as pressure relief or "spill" gates. At this instant the liquid fuel which fills compression space 43 above the plunger, begins to be forced outward through ports 44 to return to inlet chamber 42. In Fig. 16 the plunger has reached the end of its working stroke and all of this liquid has been ejected.

In Figs. 17 to 19 inclusive, the plunger is shown in each view at the start of injection, in Fig. 17 the angular position of the plunger being adjusted to give an effective stroke of approximately one-fourth the maximum, as indicated. In Fig. 18 the plunger has been turned to produce about three-fourths effective stroke and in Fig. 19 the plunger is shown turned to the position of maximum effective stroke.

Figs. 20 to 25 inclusive correspond with Figs. 14 to 19 inclusive, to illustrate a pump cylinder 5 having therein a modified form of plunger 6a whose port controlling lugs 49a are arranged to provide fixed timing of the ending of the injec-

tion period instead of the beginning. To accomplish this result the upper or port covering edges 50a are of helical formation and the lower or port uncovering edges 51a are circular. In other words, the arrangement of these edges is just the reverse of the plunger 6 shown in Figs. 14 to 19 inclusive. Figs. 20, 21 and 22 show the same plunger 6a in different positions of its stroke as previously described in connection with Figs. 14, 15 and 16. Figs. 23, 24 and 25 show the plunger 6a at the instant of start of the injection period for three different pump outputs as described in connection with Figs. 17, 18 and 19.

Figs. 26 to 31 inclusive shows a second modification of the port controlling lugs on the plunger, in this instance to produce fixed timing of the center of the injection period. For this purpose controlling lugs 49b are provided with helical control edges at both ends. Thus helical edges 50b control the start of the injection period and control edges 51b the ending of the injection period. There is no change in the position of ports 44 of cylinder bushings 5 in either of these modifications.

Again, Figs. 26, 27 and 28 show the same plunger 6b in three different positions of a single stroke, and Figs. 29, 30 and 31 show the plunger at the same position of its stroke, that is, the instant of the start of injection, but with the plunger in different angular position to produce different outputs.

In all three of these plunger constructions, that is to say, for fixed timing of the start of the injection, fixed timing of the ending of the injection, and fixed timing of the center of the injection, it will be observed from Figs. 14 to 31 inclusive that substantial amounts of fuel must be returned to the inlet fuel chamber 42 while the plunger continues to the end of its stroke after the end of the injection, the amounts being particularly large in the case of fixed timing of the beginning and fixed timing at the center of the injection.

It is important, particularly with the injection of volatile fuel such as gasoline, that the injection period be terminated with great rapidity, that is to say, substantially without lapse of time. In order to bring this about it is necessary to provide for the fuel to flow from the working space 43 to and through the two ports 44 at a low velocity so as to reduce the pressure drop in the fuel passages. This brings about quick reduction in the pressure within working space 43 and consequently quick closing of the discharge valve 46.

In order to accomplish this the plunger construction of the present invention includes a large axial passageway 110 extending from the end of the plungers 6, 6a and 6b to a point opposite the extreme ends of the port controlling lugs 49, 49a and 49b. At this point there is provided in the outer surface of the plunger a circular groove 111 of ample depth and width as shown in Figs. 4 and 14 to 31 inclusive. Groove 111 merges into the somewhat triangular spaces 112 disposed inwardly of the helical control edges 51 as shown in Figs. 14 to 19 inclusive. Connecting axial passageway 110 with groove 111 are two large cross passageways 113.

By this arrangement of fuel passageways the area of such passageways is ample to provide for the flow of the fuel from working space 43 to the spill ports 44 at low velocity so as to bring about an extremely quick reduction of the pressure with-

in the working space at the instant the spill ports are uncovered.

In addition to these passageways there are also preferably provided the diagonally opposite longitudinal grooves 114, the primary purpose of which, however, is to facilitate manufacture; specifically the milling of the port controlling lugs 49. These grooves assist in conveying the liquid from the working space 43 to the triangular spaces 112 (Fig. 14) and thence to the ports 44.

Referring again to Fig. 1, and particularly to the outlet or discharge valves 46, it has heretofore been difficult to obtain proper and reliable operation of automatic delivery valves except with the handicap of high cost of manufacture. Valves with an angular valve seat require accurate centering and guiding of the valve. Flat valves require perfect squareness between the valve seat and the valve, and a ball check valve has to be perfectly centered and guided to prevent it from striking one side of the valve seat and wearing it oval. With the usual factory production methods it is very difficult to make ball check valves which are accurately guided.

In the automatic valve construction of the present pump valve member 46 is of thimble shape having a cylindrical body portion 115 and a reduced end portion terminating in a semi-spherical valve 116. Cylindrical skirt portion 115 fits in a cylindrical guide opening which is machined in an annular projection 117 on mounting flange or plate 4. A coil spring 118 fitted within skirt 117 at one end and held at its opposite end by a removable plug 119 maintains the valve in engagement with its seat. This construction has the advantages of a ball check valve without the difficulty of guiding a loose ball.

Valve member 46 with its cylindrical skirt and semi-spherical valve end concentric with the skirt, can be produced without difficulty by ordinary production methods. Furthermore, the machining of the valve seat at the right-hand end of opening 45 is eliminated. It is only necessary to drill opening 45 concentric with the aperture in which cylindrical skirt 115 is guided. It is not necessary to machine a seat for the valve but the edges of this hole 45 are left sharp, the seat being formed by the hammering of the valve itself. In this way a very narrow seat is formed which is preferable to a wide valve seat and the hammering of its edges produces a hard surface because of the cold working of the metal.

The pump of the present construction has numerous advantages, some of which have been mentioned describing it. It will be understood that the various features of the pump may be modified as to the precise arrangement and embodiment as described herein, and that changes of this nature can be made without departing from the scope of the invention which is set forth in the appended claims.

I claim:

1. In a pump having a relatively reciprocable plunger and cylinder and whose plunger is rotatable to vary the pump output, mechanism for turning said plunger while it is reciprocating comprising a key member, a longitudinal key slot therefor in the surface of the plunger, means for positioning said key in the slot, a key driving member having a slidible connection with said key, means for mounting the same for rotation concentric with the plunger, and means for turning said key driving member.
2. In a pump having a relatively reciprocable

plunger and cylinder and whose plunger is rotatable to vary the pump output, mechanism for turning said plunger while it is reciprocating comprising a single longitudinal key slot in the surface of said plunger, a member fixed to the plunger near its outer end having a key-shaped portion projecting therefrom toward said cylinder and seated in said slot, a driving member having a slidable connection with said key-shaped portion, means for mounting the same for rotation concentric with the plunger, and means for turning said driving member.

3. In a pump having a relatively reciprocable plunger and cylinder and whose plunger is rotatable to vary the pump output, a coil spring surrounding said plunger to move the same on one of its strokes, a sleeve-like pump output control member mounted for rotation on the cylinder adjacent its inner end, means interconnecting said sleeve-like member and said plunger operable to transmit rotational movement therebetween while the plunger is reciprocating, means interconnecting the outer ends of said spring and plunger, and the inner end of said spring engaging one side of said output control member, whereby said control member, spring and plunger turn as a unit to adjust the output of the pump.

4. In a pump having a relatively reciprocable plunger and cylinder and whose plunger is rotatable to vary the pump output, a coil spring surrounding said plunger to move the same on one of its strokes, a spring retainer fixed to said plunger adjacent its outer end, a longitudinal key slot in the surface of said plunger, a key member projecting from said spring retainer and positioned thereby in said slot, a sleeve-like pump output control member mounted for rotation on said cylinder adjacent its inner end, a pair of fingers projecting from said member parallel with the plunger, said fingers having parallel faces engaging the opposite sides of said key to transmit the rotation of said control member to said plunger while the plunger is reciprocating, a shoulder on said control member adjacent said fingers, said coil spring having its ends engaging respectively said shoulder and said spring retainer, whereby said control member, spring and plunger turn as a unit to adjust the output of the pump.

5. In a multi-cylinder pump having relatively reciprocable plungers and cylinders and whose plungers are rotatable in their respective cylinders to vary the output thereof, means for turning said plungers simultaneously to vary the pump output, a housing supporting said cylinders to allow rotation of each cylinder individually to adjust the output thereof, each of said cylinders having worm gear teeth thereon, an outwardly directed aperture in said housing adjacent each cylinder, an adjusting screw disposed in said aperture having its threads engaging said teeth, means to position said screw against longitudinal movement in said aperture during rotation of the screw, and means for clamping the screw in adjusted position.

6. In a multi-cylinder pump having relatively reciprocable plungers and cylinders and whose plungers are rotatable in their respective cylinders to vary the output thereof, means for turning said plungers simultaneously to vary the pump output, a housing supporting said cylinders to allow rotation of each cylinder individually to adjust the output thereof, each of said cylinders having worm gear teeth thereon, an outwardly directed aperture in said housing adjacent each

cylinder, and an adjusting screw disposed in said aperture having its threads engaging said teeth, a pair of oppositely directed shoulders on said screw and cooperating shoulder means within said aperture to position said screw against longitudinal movement during rotation of the screw, and means for clamping said screw in adjusted position.

7. In a multi-cylinder pump having relatively reciprocable plungers and cylinders and whose plungers are rotatable in their respective cylinders to vary the output thereof, means for turning said plungers simultaneously to vary the pump output, a housing supporting said cylinders to allow rotation of each cylinder individually

15 to adjust the output thereof, each of said cylinders having worm gear teeth thereon, an outwardly directed aperture in said housing adjacent each cylinder, an adjusting screw disposed in said aperture having its threads engaging said teeth, a circular recess in the exterior of said housing, the outer ends of said adjusting screws being disposed within said recess, and a removable flexible band covering said recess.

20 8. In a multi-cylinder pump having relatively reciprocable plungers and cylinders and whose plungers are rotatable in their respective cylinders to vary the output thereof, means for turning said plungers simultaneously to vary the pump output, a housing supporting said cylinders to allow rotation of each cylinder individually

25 to adjust the output thereof, each of said cylinders having worm gear teeth thereon, an outwardly directed aperture in said housing adjacent each cylinder, an adjusting screw disposed in said aperture having its threads engaging said teeth, a circular recess in the exterior of said housing, the outer ends of said adjusting screws being disposed within said recess, and a removable flexible band covering said recess.

30 9. In a multi-cylinder pump having relatively reciprocable plungers and cylinders and whose plungers are rotatable in their respective cylinders to vary the output thereof, means for turning said plungers simultaneously to vary the pump output, a housing supporting said cylinders to allow rotation of each cylinder individually

35 to adjust the output thereof, each of said cylinders having worm gear teeth thereon, an outwardly directed aperture in said housing adjacent each cylinder, an adjusting screw disposed in said aperture having its threads engaging said teeth, a circular recess in the exterior of said housing, the outer ends of said adjusting screws being disposed within said recess, and a removable flexible band covering said recess.

40 10. In a multi-cylinder pump having relatively reciprocable plungers and cylinders and whose plungers are rotatable in their respective cylinders to vary the output thereof, means for turning said plungers simultaneously to vary the pump output, a housing supporting said cylinders to allow rotation of each cylinder individually

45 to adjust the output thereof, each of said cylinders having worm gear teeth thereon, an outwardly directed aperture in said housing adjacent each cylinder, an adjusting screw disposed in said aperture having its threads engaging said teeth, a circular recess in the exterior of said housing, the outer ends of said adjusting screws being disposed within said recess, and a removable flexible band covering said recess.

50 11. In a multi-cylinder pump having relatively reciprocable plungers and cylinders and whose plungers are rotatable in their respective cylinders to vary the output thereof, means for turning said plungers simultaneously to vary the pump output, a housing supporting said cylinders to allow rotation of each cylinder individually

55 to adjust the output thereof, each of said cylinders having worm gear teeth thereon, an outwardly directed aperture in said housing adjacent each cylinder, an adjusting screw disposed in said aperture having its threads engaging said teeth, a circular recess in the exterior of said housing, the outer ends of said adjusting screws being disposed within said recess, and a removable flexible band covering said recess.

60 75 12. In a multi-cylinder pump having relatively reciprocable plungers and cylinders and whose plungers are rotatable in their respective cylinders to vary the output thereof, means for turning said plungers simultaneously to vary the pump output, a housing supporting said cylinders to allow rotation of each cylinder individually

nism having means for operating the same disposed within said recess.

12. In a multi-cylinder pump having relatively reciprocable plungers and cylinders and whose plungers are rotatable in their respective cylinders to vary the output thereof, means for turning said plungers simultaneously to vary the pump output, a housing supporting said cylinders for individual rotation of each cylinder, mechanism for rotating each of said cylinders to adjust its individual output, and mechanism for frictionally locking said cylinders in adjusted position, both of said mechanisms having means for operating the same accessible from the exterior of said housing.

13. In a multi-cylinder pump, a plurality of cylinders arranged in parallel relation in a circular row, plungers in said cylinders and means for reciprocating the same, said plungers being rotatable in the respective cylinders to vary the output thereof, the output being controlled by a spill port in each cylinder uncovered by a lug on the plunger having an edge disposed at an angle to the axis of the plunger, an output control gear arranged to rotate on the inner end of each of said cylinders, means interconnecting said respective gears and plungers to transmit rotational movement therebetween while the plungers are reciprocating, an idler gear having teeth meshing with those of said output control gears, and an actuating gear having teeth engaging those of one of said output control gears opposite said idler gear.

14. In a pump having a relatively reciprocating plunger and cylinder, two or more spill ports in the side of the cylinder, corresponding lugs on the plunger for controlling the opening of said ports, a circumferential groove in the surface of said plunger at the lower ends of said lugs, longitudinal grooves extending therefrom to the inner end of the plunger, an axial passageway extending from the inner end of the plunger, and cross passages joining said passageway with said circumferential groove.

15. In a fuel injection pump, a cylinder having a fuel inlet port in the side thereof, a plunger therein adapted to control said port, means for reciprocating said plunger, an outlet passage from the cylinder, a valve seat in said passage, a pressure-operated valve cooperating with said seat comprising a thimble-shaped member having a cylindrical skirt and terminating in a semi-spherical valve portion, a spring acting on said valve to bias said semi-cylindrical portion against said seat, and guiding means cooperating with said cylindrical skirt.

16. In a multi-cylinder pump having a plurality of pumping units arranged in parallel relation in a circular row, each comprising a cylinder, a plunger therein and tappet mechanism, a rotary

actuating member operatively associated with the tappet mechanisms of said pumping units, a main housing member having a circular row of apertures therein to support said cylinders, a central longitudinal opening in said housing, a mounting flange for the pump adjacent one end of said housing and having a corresponding opening therein, an elongated hollow supporting member positioned in said central opening, means on said hollow supporting member to secure said housing and said mounting flange together, a shaft for said actuating member, and bearings for said shaft disposed within said hollow supporting member.

17. In a multi-cylinder pump having a plurality of pumping units arranged in parallel relation in a circular row, each comprising a cylinder, a plunger therein and tappet mechanism, a rotary actuating member operatively associated with the tappet mechanisms of said pumping units, a main housing member having a circular row of apertures therein to support said cylinders, a central longitudinal opening in said housing, a mounting flange for the pump adjacent one end of said housing and having a corresponding opening therein, an elongated hollow supporting member positioned in said central opening and having one end thereof projecting beyond the outer end of said housing, means on said hollow supporting member to secure said housing and said mounting flange together, and a tappet housing removably secured to the outer end of said main housing and having a central opening to receive and engage said hollow supporting member.

DESIRE J. DESCHAMPS.
